CLAIM

The ornamental design for a dispensing pack for volatile ingredient, as shown and described.

DESCRIPTION

FIG. 1 is a front perspective view from below and to one side of a dispensing pack for volatile ingredient, showing the new design;

FIG. 2 is a front elevational view of the dispensing pack of FIG. 1;

FIG. 3 is a rear elevational view of the dispensing pack of FIG. 1;

FIG. 4 is a top plan view of the dispensing pack of FIG. 1, the bottom plan view being a substantially a mirror image thereof;

FIG. 5 is a right side elevational view of the dispensing pack of FIG. 1, the left side elevational view being substantially a mirror image thereof;

FIG. 6 is a front perspective view, corresponding to FIG. 1, from below and to one side of a dispensing pack for volatile ingredient, showing an alternative embodiment of the new design, the sole difference being in the exact shape of the pair of openings located at either side of the top portion of the dispensing pack;

FIG. 7 is a front elevational view of the dispensing pack of FIG. 6;

FIG. 8 is a rear elevational view of the dispensing pack of FIG. 6;

FIG. 9 is a top plan view of the dispensing pack of FIG. 6, the bottom plan view being substantially a mirror image thereof; and,

FIG. 10 is a right side elevational view of the dispensing pack of FIG. 6, the left side elevational view being substantially a mirror image thereof.
